ELECTRIC TORCH WHICH FLOATS LAMP
UPPERMOST IN WATER

Charles Wallace Saunders, Bramley, England, assignor to The General Electric Company Limited, London, England

Application May 24, 1943, Serial No. 488,164
In Great Britain June 3, 1942

15 Claims. (Cl. 9—8.3)

This invention relates to electric torches and, more particularly, to torches which are suitable for use at sea. The object of the invention is to provide a torch of simple construction which will, when immersed in water, float with the bulb clear of the water. Such a torch is of use in a number of circumstances, one of the most important at the present time being that it may act as an indication by which a rescue vessel may be guided to a person in the water and in need of being rescued. Torches in accordance with the invention are made watertight, and are therefore suitable for use in damp atmospheres and in circumstances in which they are liable to accidental immersion in water, even though, in these latter cases, the ability of the torch to float bulb-upmost in water is not necessary.

A further object is the provision of an electric torch construction such that it may be held in reserve for considerable periods ready for use, irrespective of storage conditions, and offer maximum reliability when required for use, as for example in an emergency.

The invention is illustrated in two alternative constructions in the accompanying drawing, in which:

Fig. 1 is a longitudinal sectional view of the torch in one construction,

Fig. 2 is a partial view of the lower end of the torch, and

Fig. 3 is a diagrammatic longitudinal sectional view of an alternative construction of torch.

The torch illustrated in Fig. 1 comprises a watertight tubular casing 1, which at the lamp end has a screwed portion 2 of reduced diameter. Onto the portion 2 is screwed a cap 3, and a rubber washer 4 is clamped between the cap and the part 2. The top 5 of the cap 3 is apertured to form a socket for the lamp 6, which is protected by a dome 7 of translucent synthetic resin coloured red, which is screwed into a socket 8 formed outside the top of the cap 3. The joint between the socket 8 and the dome 7 is made water-tight.

In the other end of the casing 1 is fixed a plate 10, the end of the casing extending beyond the plate, and forming a shoulder portion 11. On the outside of the plate 10 is mounted a screwed portion 12 of a diameter which leaves an annular space between it and the shoulder 11, and over the end of the part 12 is screwed a centrally apertured cap 13, a flexible rubber cap 14 being clamped between the parts 12 and 13. Mounted in a sleeve 15 on the plate 10 is a plunger 16 which is urged outwardly by a spring and has its

inner end 16' extending within the casing 1. The flattened head of the plunger 16 lies close against the middle of the diaphragm portion of the rubber cap 14.

Through apertures in the casing 1 extend two oppositely placed studs 17, carried on the ends of a bow spring 17' located between the screwed part 12 and the shoulder 11 of the casing.

Over the end of the outer casing passes freely a centrally apertured switch-operating cap 18, having an inwardly directed boss 19 surrounding the aperture, and oppositely disposed bayonet slots 20 in which the studs 17 engage. A sealing wire 21 is soldered between one of the studs 17 and a point on the cap 18 to prevent the cap being pressed further onto the casing before the torch is to be put in use.

Inside the casing and located at its lower end in a shallow recess in the plate 10 is an insulating tube 22 of cardboard having an apertured insulating disc 23 at its lower end through which passes the inner end 16' of the plunger 16, while the other end of the tube 22 is located by fitting snugly within the reduced upper end 2 of the casing 1. Within the tube 22, and against the bottom disc 23, is placed the battery 24, with central terminal 25 at its upper end. Fitted closely over this terminal is one end of a split metal tube 26, which forms the conducting spacing member between the battery and the lamp 6 of the torch. An insulating fibre disc 27 fixed on the lower end of the spacing member 26 covers the top of the battery 24 and fits closely within the insulating tube 22. Another fibre disc 28 fixed on the upper end of the spacing member 26 also fits closely within the cardboard tube 22. Within this end of the spacing member 26 is fixed a spring plunger contact 29 adapted to make constant contact with the terminal 6' of the lamp. A helical spring 30, stronger than the spring urging the contact plunger 29, is soldered to the underside of the lamp socket 5 and is compressed between the lamp socket 5 and the fibre washer 28 on the spacing member 26. It will be seen that the spring 30 presses the spacing member 26 and battery 24 onto the bottom 23 of the cardboard tube 22 and the latter onto the plate 10 of the casing 1.

A lanyard 31 to enable the torch to be attached to the person, is fastened to a pin 32 passed through the inturned boss 19 of the switch operating cap 18.

To test the torch, and to determine that it is in working order without breaking the seal 21, it is only necessary to insert, say, a match or a

pencil through the opening in the cap 18 and depress the switch plunger 16 to make contact with the battery 24. An implement for this purpose may be provided on the lanyard 31.

To operate the lamp the seal wire 21 is broken, whereupon the switch operating cap 18 can be freely depressed against the spring of the switch plunger 16 and, when the cap 18 is depressed to its full extent, a part turn of the cap about its axis will lock the plunger switch 16 in the "on" position, the pins 17 engaging in the circumferential parts of the slots 20. Alternatively, to use the lamp for Morse signalling, the cap 18 is alternately pressed inwards and released.

Preferably the plunger switch is so dimensioned as to make contact with the bottom of the battery 24 without the cap 18 being depressed to its full extent. A further depression of the cap 18 which will enable the pins 17 to engage and lock in the circumferential parts of the bayonet slots 20, pushes in the plunger 16 so far that the battery is slightly raised off the disc 23, with the consequent lifting of the spacer member 26 and compression of the spring 30. This will not materially alter the load upon the contact terminal 6' of the lamp, because the spring contact 29 at the top of the spacing member 26 will yield against its comparatively light spring, and the lamp terminal is thus protected against any violent shock that might lead to injury to the lamp or displacement of the lamp in its socket.

A modified construction of torch according to the present invention is shown in Fig. 3. Here the spacing member 40 is not mounted directly on the terminal 41 of the battery 42, but a spiral spring 43 is soldered to the underside of the disc 44 on the lower end of the spacing member and this spring carries at its outer end a shallow cap 45 adapted to seat itself on the terminal 41. This arrangement may be preferred, because in practice it is found that the batteries suitable for these torches do not always have terminals of the same diameter, and sometimes the terminal extends only very little above the top surface of the battery, so that the spacing member cannot always be relied upon to fit closely and firmly onto the terminal as in the construction of Fig. 1. In Fig. 3, moreover the disc 46 on the upper end of the spacing member 40 lies against a rigid cylindrical stop member 47 mounted on the underside of the lamp socket 48, instead of the disc lying against a helical spring as in the arrangement of Fig. 1. The spacing member has a spring controlled push contact 49 to ensure unbroken contact with the lamp terminal 50.

At the other end of the torch, the battery 42 rests on the insulating disc 51, forming the bottom of the insulating sleeve 52 containing the battery and spacing member. The switch plunger 53 slides in a sleeve 54 mounted in a disc 55 soldered across the watertight casing 56 and passes upwards through a central aperture in the disc 51. It is adapted to be pressed inwards towards the battery 42, against the action of the spring 57, when the switch operating cap 58 is pressed upwards, the boss 59 of cap 58 bearing upon the head of the plunger 53 through the rubber diaphragm 60.

The cap 58 is provided as before with bayonet slots 61, but these instead of co-operating with pins carried by a bowed spring as in the arrangement of Fig. 1, work on set screws 62, having plain shoulders working freely in the slots.

61, and mounted in a ring 63 soldered on the flange 64 of the extension member 65 of the casing 56.

The cap 58 may be used as before after the sealing wire has been broken, either for signalling with the torch or to lock the switch in the "on" position. In the latter position the plunger 53 will preferably raise the battery slightly from the disc 51, compressing the spring 43 between the battery 42 and spacing member 40.

In other respects the construction of the torch illustrated in Fig. 3 is substantially the same as that in Fig. 1.

15. I claim:

1. An electric torch comprising a water tight tubular casing including a deformable portion, a lamp socket and lamp mounted at one end of said casing, a battery mounted at the other end of said casing, a rigid conducting spacing member disposed between the lamp and battery within the casing and of a length to ensure that the torch will float in water with the lamp end uppermost, and switch means adapted to be operated through said deformable portion of the casing and to urge the battery and conducting spacing member towards the lamp.

2. An electric torch comprising a water tight tubular casing including a deformable portion, 30 a lamp socket and lamp mounted on one end of said casing, a battery mounted at the other end of said casing, a rigid electrically conductive member disposed between said lamp and battery to space the same apart and electrically connect a terminal of said lamp to a terminal of said battery, said member being sufficiently long to ensure that the torch will float in water with the lamp end uppermost and at or above water level, and switch means operable through said deformable portion to close the circuit between the other terminal of said battery and the other terminal of said lamp, and to urge said battery and spacing member towards the lamp upon closing of the switch.

3. An electric torch as set forth in claim 2, wherein a resilient electrically conductive member electrically interconnects the spacing member with the first named terminal of the lamp, and wherein another resilient member urges said spacing member and said battery away from said lamp whereby upon closing of said switch, said battery and spacing member are displaced toward said lamp and both said resilient members compressed.

4. An electric torch comprising a water tight tubular casing including a deformable portion, a lamp socket and lamp mounted on one end of said casing, a battery mounted at the other end of said casing, a rigid electrically conductive member disposed between said lamp and battery to space the same apart and electrically connect a terminal of said lamp to a terminal of said battery, said member being sufficiently long to ensure that the torch will float in water with the lamp end uppermost and at or above water level, a resilient electrically conductive member electrically and physically interconnecting said spacing member with said lamp terminal, and switch means operable through said deformable portion to close the circuit between the other terminal of said battery and the other terminal of said lamp, and to urge said battery and spacing member towards the lamp upon closing of the switch.

5. An electric torch comprising a water tight

tubular casing including a deformable portion, a lamp socket and lamp mounted on one end of said casing, a battery mounted at the other end of said casing, a rigid electrically conductive member disposed between said lamp and battery to space the same apart and electrically connect a terminal of said lamp to a terminal of said battery, said member being sufficiently long to ensure that the torch will float in water with the lamp end uppermost and at or above water level, a fixed stop member located within the casing in the region of the lamp socket, means for supporting in the casing the end of the spacing member remote from said battery, a resilient electrically conductive member electrically interconnecting said remote end of the spacing member with said lamp terminal, a resilient electrically conductive member electrically and physically connecting said battery terminal and said other end of the spacing member, and switch means operable through said deformable portion to close the circuit between the other terminal of said battery and the other terminal of said lamp, and to urge said battery and spacing member towards the lamp upon closing of the switch.

6. An electric torch comprising a water tight tubular casing including a deformable portion, a lamp socket and lamp mounted on one end of said casing, a rigid electrically conductive member disposed between said lamp and battery to space the same apart and electrically connect a terminal of said lamp to a terminal of said battery, said member being sufficiently long to ensure that the torch will float in water with the lamp end uppermost and at or above water level, an insulating tube within the tubular casing and surrounding both the battery and a rigid conductive spacing member discs within the insulating tube for locating both ends of said spacing member in said tube, and switch means operable through said deformable portion to close the circuit between the other terminal of said battery and the other terminal of said lamp, and to urge said battery and spacing member towards the lamp upon closing of the switch.

7. An electric torch comprising a water tight tubular casing including a deformable portion, a lamp socket and lamp mounted on one end of said casing, a battery mounted at the other end of said casing, a rigid electrically conductive member disposed between said lamp and battery to space the same apart and electrically connect a terminal of said lamp to a terminal of said battery, said member being sufficiently long to ensure that the torch will float in water with the lamp end uppermost and at or above water level, said conductive member comprising a split metal tube having one end clamped tightly on to the central terminal of the battery, a spring member to bias the other end of said tube away from the lamp socket, a resilient spring contact between said other end of the tube and said terminal of the lamp, an insulating tube within the tubular casing and surrounding both the battery and the split tube, discs within the insulating tube for locating both ends of the split tube therein, and switch means operable through said deformable portion to close the circuit between the other terminal of said battery and the other terminal of said lamp, and to urge said battery and spacing member towards the lamp upon closing of the switch.

8. An electric torch comprising a water tight tubular casing including a deformable portion, a lamp socket and lamp mounted on one end of

said casing, a battery mounted at the other end of said casing, a rigid electrically conductive member disposed between said lamp and battery to space the same apart and electrically connect a terminal of said lamp to a terminal of said battery, said member being sufficiently long to ensure that the torch will float in water with the lamp end uppermost and at or above water level, an insulating tube within the tubular casing and surrounding both the battery and the rigid conductive spacing member, discs within the insulating tube for locating the ends of the spacing member in said tube, a fixed stop member located within the casing in the region of the lamp socket, a yielding spring contact between said battery terminal and the adjacent end of the spacing member, and switch means operable through said deformable portion to close the circuit between the other terminal of said battery and the other terminal of said lamp, and to urge said battery and spacing member towards the lamp upon closing of the switch.

9. An electric torch comprising a water tight tubular casing including a deformable portion, a lamp socket and lamp mounted on one end of said casing, a battery mounted at the other end of said casing, a rigid electrically conductive member disposed between said lamp and battery to space the same apart and electrically connect a terminal of said lamp to a terminal of said battery, said member being sufficiently long to ensure that the torch will float in water with the lamp end uppermost and at or above water level, and switch means operable through said deformable portion to close the circuit between the other terminal of said lamp and the other terminal of said lamp, and to urge said battery and spacing member towards the lamp upon closing of the switch, said switch means including a yielding spring contact adapted to be brought into engagement with a battery terminal by pressure exerted through said deformable portion of the casing, the spring of said spring contact returning said deformable portion to its initial position when pressure is released.

10. An electric torch comprising a water tight tubular casing including a deformable portion, a lamp socket and lamp mounted on one end of said casing, a battery mounted at the other end of said casing, a rigid electrically conductive member disposed between said lamp and battery to space the same apart and electrically connect a terminal of said lamp to a terminal of said battery, said member being sufficiently long to ensure that the torch will float in water with the lamp end uppermost and at or above water level, switch means operable through said deformable portion to close the circuit between the other terminal of said battery and the other terminal of said lamp, and to urge said battery and spacing member towards the lamp upon closing of the switch, said switch means including a yielding spring contact adapted to be brought into engagement with a battery terminal by pressure exerted through said deformable portion of the casing, the spring of said spring contact returning said deformable portion to its initial position when pressure is released, and a movable rigid cover over said deformable portion for applying pressure to said deformable portion when moved to operate said switch means, said cover including means for locking the same in switch operative position when moved.

11. An electric torch as set forth in claim 10 wherein the rigid cover is fixed by a breakable

seal in the inoperative position of the switching means, and wherein said cover has an aperture through which a probe can be inserted to operate the switching means by pressure on the deformable portion of the casing for testing purposes.

12. An electric torch as set forth in claim 7 wherein the switch means includes a yielding spring contact adapted to be brought into engagement with the battery terminal by pressure exerted through the deformable portion of the casing and in which the spring of said spring contact returns the deformable portion of the casing to its initial position when pressure is released.

13. An electric torch as set forth in claim 7 wherein the switch means includes a yielding spring contact adapted to be brought into engagement with the battery terminal by pressure exerted through the deformable portion of the casing and in which the spring of said spring contact returns the deformable portion of the casing to its initial position when pressure is released, and wherein the torch has a movable rigid cover over the deformable portion which, when moved, operates said switch by pressure on said deformable portion, and which includes

means for locking said cover in switch operative position.

14. An electric torch as set forth in claim 8 wherein the switch means includes a yielding spring contact adapted to be brought into engagement with the battery terminal by pressure exerted through the deformable portion of the casing and in which the spring of said spring contact returns the deformable portion of the casing to its initial position when pressure is released.

15. An electric torch as set forth in claim 8 wherein the switch means includes a yielding spring contact adapted to be brought into engagement with the battery terminal by pressure exerted through the deformable portion of the casing and in which the spring of said spring contact returns the deformable portion of the casing to its initial position when pressure is released, and wherein the torch has a movable rigid cover over the deformable portion which, when moved, operates said switch by pressure on said deformable portion and which includes means for locking said cover in switch operative position.

CHARLES WALLACE SAUNDERS.
